TELEPHONE TRANSMISSION SYSTEM

Howard H. Smith, Chicago, Ill., assignor to Associated Electric Laboratories, Inc., Chicago, Ill., a corporation of Delaware

Application January 2, 1936, Serial No. 57,116

4 Claims. (Cl. 179—15)

The present invention relates to telephone transmission systems, but is concerned more particularly with multi-channel telephone transmission systems.

5 The object of the invention is the production of a new and improved system for providing for multi-channel telephone transmission.

GENERAL DESCRIPTION

10 The system disclosed herein, like previous systems for providing multi-channel operation over the same common circuit path, is based on the fact that a telephone circuit may serve as a transmission medium for a frequency band many times wider than the frequency band necessary for ordinary telephone conversation. It has been found that if a band of voice frequencies 3000 cycles wide, extending from about 200 cycles to about 3200 cycles is transmitted uniformly, to the exclusion of all other frequencies which may be contained in the voice of a speaker, a commercial quality of intelligibility results. Now, an inter-exchange or inter-city telephone circuit is ordinarily capable of transmitting or carrying frequencies satisfactorily up to 30,000 cycles, or higher. It is obvious, therefore, that, if a suitable transmission system can be devised, several conversational channels may be secured by arranging that the extended frequency-transmitting characteristics of the telephone circuit be utilized.

15 The novel system disclosed herein is based on the principle of multiplying all of the necessary frequencies of a telephone conversation by a sufficiently large common factor that the resulting transmission frequencies compose a band of a width commensurate with the frequency-carrying capacity of the circuit. This common factor may be five, for example, if the chosen upper frequency limit of the circuit is slightly in excess of 16,000 cycles, and if 3200 cycles is chosen as the upper limit of voice input. This frequency multiplication is obtained by first recording a small portion of a train of voice currents; reproducing these recorded voice currents at a rate which is five times as fast as they were recorded; and sending the reproduced high-frequency currents over the line.

20 The recording may take place continuously, while the reproducing and transmission over the line takes place intermittently, occupying one-fifth the line time. Allowing for inter-channel switching time intervals, it has been found that under the assumption above made four conversations may be sent over the line during the

same time period by arranging that the times of reproduction and retransmission of the high frequency currents resulting from the four conversational records be interspersed. At the distant end of the circuit, the incoming high frequency voice currents are recorded intermittently as concerns any individual conversation, and are reproduced at the original recording rate, whereby the reproduction of the received and recorded currents is continuous and at the original rate. 10 By making the time units involved sufficiently short, the delay occasioned by the recording and reproduction may be reduced sufficiently that the persons conversing are not aware that the transmission is not proceeding uninterruptedly. 15

With the novel arrangement just outlined, the time elapsing during the transmission of telephone conversations is divided into small unit intervals, and each unit interval is further subdivided into four sub-intervals, each sub-interval 20 being allotted to one of the conversing subscribers. This allotting, together with the recording and transmitting over the common line is accomplished by what may be termed a distributor. 25 This distributor allots regularly recurring intervals of time to each of the four incoming channels, while a receiving distributor at the distant end of the line makes a similar allotment of the sub-intervals of receiving time.

It has been chosen to illustrate the invention as applied in obtaining four-channel, two-way telephone transmission over an inter-city telephone line.

Description of drawings

30 Referring now to the accompanying drawings, Fig. 1 shows an end view of the mechanical construction of a combined transmitting and receiving distributor designated generally as the distributor D1. Fig. 2 is a side view of the receiving distributor D1. Fig. 3 is a circuit drawing showing the distributor D1 used as the transmitting and receiving distributor at one end of the telephone line TL, at the other end of which the distributor D2 shown in Fig. 4 operates to receive from the transmitting portion of the distributor D1 and to transmit to the receiving portion of the distributor D1. 35

DETAILED DESCRIPTION

40 The invention having been described generally, a detailed description will be given, for which purpose the mechanical construction of distributor D1 will first be described. 45

The distributor D1

The distributor D1 consists of certain parts mounted on the base 1. It comprises essentially a central shaft 2, journaled to rotate within a hollow shaft 3, which in turn is journaled to rotate within the sleeve 13, supported by the housing 12. The shafts 2 and 3 are arranged to be rotated in opposite directions and at different speeds by the motor 4, on whose shaft 5 the gears 6 and 8 are mounted. The gear 6 drives a reducing gear 7 which is rigidly secured to the central shaft 2. The motor 4 is assumed to be rotatable at a constant speed in a clockwise direction as viewed from the left, whereby the central shaft 2 rotates in a counterclockwise direction.

The gear 8, rotating in a clockwise direction because it is secured to shaft 5 of the motor, drives the reverse gear 9 in a counter-clockwise direction, whereby the auxiliary gear 10 is driven in the same direction. The gear 10 drives the reducing gear 11 in a clockwise direction. Since the gear 11 is secured rigidly to the hollow shaft 3, the shaft 3 is rotated in a clockwise direction, but at a much lower rate than the rotation of the central shaft 2 in a counter-clockwise direction.

The track wheel 14 is secured to the hollow shaft 3 at the left end of the shaft, and the brush wheel 15 is secured to the left end of the central shaft 2, whereby the wheels 14 and 15 are rotated respectively by the shafts 3 and 2, the wheel 14 revolving relatively slowly in a clockwise direction while the brush wheel 15 revolves at a relatively rapid rate in a counter-clockwise direction.

The track wheel 14 has the track disc 18 clamped between its rim and the disc clamp 19 to provide two sound tracks on the disc 18; an outer track for temporarily recording telephone conversations to be transmitted over a multi-channel line, and an inner track for temporarily recording conversations received over the multi-channel line before they are placed on local single-channel lines. The two sound tracks on the disc 18, carried by the track wheel 14, are separated by the stiffening rings 20 and 21 which are provided to render the relatively thin track disc 18 sufficiently stiff that it is not distorted materially by the pull of the erasing electromagnets which are hereinafter described. The track disc is made thin enough that a sound record magnetically impressed on one side may be reproduced by passing a pickup coil along the other side.

As the disc 18 is revolved in a counter-clockwise direction, and considering now the outer or transmitting sound track (lying outside the stiffening rings 20 and 21) the disc at any instant may be considered as divided into quadrants by the four groups of electromagnets mounted on the stationary sending ring 16. Each of these groups of magnets corresponds to a separate telephone transmitting channel as is indicated in Figs. 3 and 4, wherein the channels have been designated as A, B, C, and D, respectively. Magnet 41 is one of the three horseshoe electromagnets of channel A; magnet 42 is one of the three magnets of channel B; magnet 43 is one of the three magnets of channel C; and magnet 44 is one of the three magnets of channel D. Voice currents passing through the coil 41 as the disc 18 is rotated in a clockwise direction leave a magnetic voice record on the outer sound track of disc 18, as the disc 18 is assumed to be made of magnetic material of relatively high retentivity;

steel, for example. Magnet 42 of channel B may be likewise leaving a voice-current record on the portion of the disc passing by its pole faces, as are magnets 43 and 44 of channels C and D.

Considering now a portion of the outer sound track of disc 18 that has just passed the magnet 42 of channel B, this portion continues to be rotated and a magnetic sound impression is left on the disc, which impression or record is extended until the portion in question starts to approach the group of magnets containing magnet 41. When magnet 41 of this group is reached, the record is completely removed from the sound track because the portion of the track under the magnet 41 is saturated by the strong magnetic flux emanating from the poles of magnet 41. As the portion of the sound track travels still further, magnet 35, which is less strongly magnetized than magnet 41, and in the reverse direction, removes the effect of the saturation of the sound track and restores the portion to a normal non-magnetized state. Therefore, when the portion of the disc in question progresses further and passes under the recording magnet 41 of channel A, all evidence of the previous sound record has been removed and the portion of the disc is in a receptive condition for the impression of a further magnetic sound record.

What has been described is, of course, a continuous process, as the disc wheel 14 is in continuous motion and is therefore continuously moving the track disc 18. As a result, the portion of the disc between a recording magnet, such as 42, and the next succeeding erasing magnet, such as 34, contains a portion of a spoken message the length of which depends upon the amount of time required for the disc to travel from the recording magnet to the next succeeding erasing magnet. Therefore, in order that none of the recorded speech be lost, it is essential that a reproduction be made of what is recorded once during each successive time interval of a length no longer than the length of time required for a portion of the disc to travel from a recording magnet such as 42 until it comes under the influence of the next succeeding erasing magnet such as 34.

The reproduction and transmission of the recorded voice currents is accomplished by the transmitting reproducing magnet 28, which is mounted on the rim of the brush wheel 15 near its periphery and counterbalanced by the weight 30, mounted at a point diametrically opposite the horseshoe electromagnet 22. The reproducing, transmitting, magnet 28 is maintained in constant connection with the transmitting circuit through the medium of the slip rings 25 and the stationary contact brushes 24, while the receiving, recording magnet 29, mounted near the inner edge of the rim of the brush wheel 15 is similarly maintained in connection with the receiving circuit through the rings 27 and the stationary contact brushes 26. The weight 31 is mounted so as to counter-balance the electromagnet 29.

Since the distributor D1 is a combined transmitting distributor and receiving distributor, it is provided with receiving, reproducing stationary magnets in addition to the transmitting, recording stationary magnets. These receiving, recording magnets for channels A, B, C, and D are respectively 71, 72, 73, and 74, all of which are shown in Figs. 3 and 4, in addition to being shown in Figs. 1 and 2. These magnets are mounted on the adjustable stationary receiving ring 17, whose

adjustable feature is provided for a purpose which will be made clear in a subsequent part of the description. Adjustment of the receiving ring 17 is provided by turning the worm 22 in the desired direction, such as by inserting a screw driver or similar instrument in the slotted end of the shaft which supports the worm 22. The worm 22 cooperates with the worm gear cut on the periphery of receiving ring 17, which ring is 10 rotatably mounted on a portion of the bearing sleeve 13. The group of magnets carried by the receiving ring 17 may thereby be adjusted with respect to the groups of magnets carried by the transmitting ring 16.

15 A further feature of adjustment of the distributor is provided by the worm 23 and the associated worm gear secured around the housing of the driving motor 4. The motor 4 is mounted in brackets 32 and 33 so that it can be rotated 20 bodily when the worm 23 is turned in the desired direction, which turning is facilitated by the slot in the end of the supporting shaft. The desirability of this adjustment will be made apparent hereinafter.

25 *The system*

Referring now particularly to Figs. 3 and 4, it is to be noted that the telephone line TL extends between exchange 1 and exchange 2. These exchanges are assumed to be located in different cities, whereby the interconnecting line TL is sufficiently valuable because of its length that it is economical to supply additional terminal equipment in order to provide the additional telephone channels. A manual switchboard is assumed to be provided in each of the exchanges. The jack J1 is one of the jacks at the manual switchboard of exchange 1, while the jack J2 is one of the jacks at the manual switchboard of exchange 2. These two jacks, as will be more 40 fully pointed out hereinafter serve as the terminals of one of the channels (channel A) which is provided over the common line TL. The line equipment LE1 is associated with the jack J1. This line equipment may be any standard equipment such as is used with carrier-current telephone systems, and it is arranged to close a lighting circuit for the lamp L1 when the operator at 45 exchange 1 is to be signalled from exchange 2, which signalling is carried on by signalling current in the range of voice frequencies, as is well known. The line equipment LE2 and the lamp L2 are associated with the jack J2 in the second exchange to perform similar functions. Each 50 of the three other two-way channels provided over the trunk line TL may be similarly equipped, although the jacks and associated line equipment of these other channels have been omitted for the sake of simplicity.

55 The balance coil 55 is introduced between the line equipment LE1 and the distributor D1. This balance coil, along with the artificial line 56 operates in the well-known way to provide separate voice channels outgoing from and incoming to the jack J1. The outgoing channel extends from the mid-points of the line windings of the balance coil to the recording magnet 41, while the incoming channel extends from the reproducing magnet 71 to the lower winding of coil 55. When 60 the artificial line 56 is properly balanced to match the local line connected with the jack J1 by way of the manual switchboard, voice currents received from the reproducing magnet 71 are repeated alike to the artificial line 56 and the local line, and no voice currents are driven through

the transmitting branch to the recording magnet 41. The reason for this arrangement becomes apparent when it is pointed out that otherwise voice currents received from the reproducing magnet 71 would be transmitted to the recording magnet 41 and sent back over the circuit in the opposite direction, which would tend to produce undesirable "singing". The balance coil 65 and the artificial line 66 are provided in association with the jack J2 for the same purpose.

At the distributor D1, it is to be observed that the windings of the erasing electromagnets, such as erasing magnet 34 associated with channel A, are all connected in series, and that current from 15 the exchange battery flows through this series circuit under the control of the regulating rheostat 45 to magnetize the erasing magnets sufficiently to bring the portion of the sound track under the influence of the respective magnets to 20 the saturation point in order to remove previously made voice records. Since disc 18 is rotated in a clockwise direction, the saturated parts of the disc then come under the influence of the restoring magnets such as 35. These restoring 25 magnets are connected in series with each other and are supplied with current from the exchange battery by way of the regulating rheostat 46. As is evident from the fact that the connections are made in reverse direction to the restoring 30 magnets, the magnetic flux emanating from the restoring magnets is in the opposite direction to that emanating from the saturating erasing magnets. The result of this is that the portion 35 of the disc passing under a magnet such as 35 would be demagnetized and then saturated in the opposite direction if the restoring magnets were of the same strength as the erasing magnets. However, the restoring magnets are of 40 lesser strength than the erasing magnets, for which reason the previously effected saturation is undone only to the extent that the portion of the sound track coming from under the influence of a restoring magnet such as 35 has little or no magnetism. This condition may be 45 regulated somewhat by an adjustment of the rheostat 46.

Considering the receiving portion of the distributor D1, the erasing magnets such as 36 are connected in a series circuit controlled by the 50 rheostat 47, while the restoring magnets such as 37 are connected in a series circuit controlled by the rheostat 48.

As previously pointed out, the magnet 28 is the travelling reproducing transmitting magnet, being mounted on the brush wheel 15, Fig. 1, so that it moves relatively rapidly in a counter-clockwise direction, while the magnet 29 is the travelling receiving recording magnet, also moving in a counter-clockwise direction. The amplifier 57 55 is the outgoing line amplifier used to amplify the high-frequency outgoing voice currents before they reach the common line TL. The artificial line AL is provided to balance the characteristics of the trunk line TL, whereby the balance 60 coil 58 may serve to prevent outgoing voice currents from reaching the incoming branch associated with the amplifier 60, as discussed in connection with the balance coil 55. The incoming voice currents, on the other hand, are transmitted 65 through the incoming line amplifier 68, which leads into the common receiving recording magnet 29 by way of brushes 26 and slip-ring 27. In exchange 2, the line TL is provided with balance 70 coil 68, artificial line 69, input amplifier 67, and 75

output amplifier 10, corresponding respectively, to the parts 58, 59, 51, and 60 in exchange 1.

The distributor D2 may be like the distributor D1; the transmitting and receiving magnets 38, 39 correspond to the magnet 28, 29 of the distributor D1; the stationary recording magnets 61 to 64 correspond respectively to the recording magnets 41 to 44 of the distributor D1; and the stationary reproducing magnets 51 to 54 associated with the receiving portion of the distributor D2, correspond respectively to the stationary reproducing magnets 71 to 74 of the receiving portion of the distributor D1.

Operation of the system

For the successful and satisfactory operation of the system, it is necessary that the synchronous motor 4 of the distributor D1 drive its shaft 5 in synchronism with the corresponding shaft of the distributor D2. This result may be obtained, for example, by driving the motors from the same system of alternating-current power distribution, or the driving system may depend largely upon local power with a speed correction obtained over an interconnecting line as is done for instance in multiplex telegraphy or in systems for maintaining synchronism in the transmission of still pictures by wire. When the system is to be started into operation, the motors of the distributors at the two exchanges are started and are caused to run in synchronism.

Phasing the distributors

In order that the system operate as intended, it is further necessary to bring each receiving distributor into phase with the transmitting distributor from which it receives. For this purpose, a source of tone current may be connected to the tip and ring conductor of the jack J1, while the person in charge of the equipment at exchange 2 connects a receiver to the jack J2 and listens for the tone which is applied through the jack J1. The receiving ring of the distributor D2 (corresponding to ring 17 of the distributor D1) is then adjusted by the worm and gear arrangement previously described, until the tone applied at the jack J1 is heard at the jack J2 as a continuous uninterrupted tone. This adjustment may be verified by associating the test receiver with the other three jacks (not shown) corresponding to channels B, C, and D. When the adjustment is correct, none of the tone applied to jack J1 can be heard at any other one of the jacks.

The receiving portion of the distributor D1 may be brought into phase with the transmitting portion of the distributor D2 by a similar method. For this purpose, the tone source may be connected to the talking conductors at the jack J2, and a receiver may be connected to the jack J1. The worm 22 is then turned in one direction or the other until the worm gear cut on the periphery of the receiving ring 17 drives the ring into the correct position, in which position the tone applied at the jack J2 will be heard at the jack J1 as a continuous tone and will not be heard at all at any one of the other three jacks associated with the system and corresponding respectively to channels B, C, and D. When this has been accomplished, the four two-way channels over the inter-exchange trunk line TL are available for service.

Setting up connections

As is indicated by the common-connection sym-

bols associated with the jack J1, this jack may be multiplied with other positions of the switchboard so that the associated channel may be used by any one of the number of operators. Assuming that a call is received at exchange 1 and is to be completed through exchange 2, the operator at exchange 1 who receives the call may make the usual tip busy test on the sleeves of the jacks such as J1. Assuming that the jack J1 tests idle, the operator may insert the plug (not shown) of her cord circuit into the jack J1, causing this channel thereby to test busy at the other test positions. The operator may now project ringing current over the channel A through the jack J1. It is assumed that the line equipment LE1 contains equipment similar to the so-called composite ringing equipment for responding to ringing current by relaying current at a selected frequency within the voice range for signalling purposes. This relayed current traverses the channel-A portion of the distributor D1 and passes over the trunk line TL and is repeated through the channel-A receiving portion of the distributor D1 to the line equipment LE2 associated with the jack J2. The line equipment LE2 is assumed to have responding equipment therein which responds to the relayed ringing signal by lighting the line lamp L2 as a call signal to the operator. The operator in exchange 2 may now respond to this signal by inserting the plug of an idle cord circuit into the jack J2 to extend the connection.

Ring-off and other supervision may be controlled by relayed signal currents lying within the voice-frequency range, as pointed out in connection with the original signalling operation above described.

Transmission of voice currents

It may be assumed now that separate inter-exchange connections exist by way of the four channels, A, B, C, and D, of the line TL, under which condition the maximum use may be made of the trunk line TL. A description will now be given of the operations that take place during one or more cycles of operation of the distributor. It may be assumed that each of the four subscribers in exchange 1 is talking at the moment the description covers. Under this condition, voice currents are being received continuously at each of the recording magnets 41, 42, 43, and 44 of the transmitting portion of the distributor D1; the outer sound track of the track disc 18 is being driven continuously in a clockwise direction under the pole pieces of the magnets 41 to 44 at a rate which is sufficient to elongate the recorded magnetization curves sufficiently that they may be reproduced clearly. At the same time, the transmitting reproducing magnet 28 of the distributor D1 is being driven in a counter-clockwise direction at an angular velocity about five times that of the track disc 18, whereby the magnet 28 makes one complete revolution in the time required for a portion of the disc 18 to pass from under the poles of a recording magnet such as 42 and travel far enough to reach the influence of the next succeeding erasing magnet such as 34. Considering now channel B in particular, and at a time when the reproducing transmitting magnet 28 is passing over the pole pieces of the recording magnet 42, the portion of the outer sound track of the disc 18 which is at that moment under the pole pieces of magnet 42 travels until it is about to come under the influence of the erasing magnet 34. At this point, the magnet 28, which in the meantime has rotated around over channels C, 75

D, and A, comes from the field of influence of the magnet 34 in time to resume the reproduction and transmission of the record produced by magnet 42 before an unreproduced portion of the message is erased. The next portion, therefore, of the message being received over channel B from the local subscriber in exchange 1 is quickly transmitted over the line by the reproducing and transmitting action of the travelling magnet 28 and at 5 a rate which is about five times the recording rate. 10 This action occurs on each revolution of the travelling magnet 28, and it occurs for each of the four channels.

It is to be noted that about one-fifth of the line 15 time is unused in the embodiment illustrated owing to the necessary space occupied by the magnet groups such as 34, 35, 41. This time may be reduced of course, by making the magnets smaller or preferably by enlarging the radius of the 20 brush wheel 28 and of the magnet rings 16 and 17, along with the radius of the track disc 18. It is to be observed further that, although a considerable disturbance may be created when the traveling magnet 28 passes over an erasing magnet such 25 as 35, the current resulting from this disturbance reaches the distant receiving magnet 39 at a time when this magnet also is passing over an erasing magnet, for which reason the disturbance is not recorded at the distant end and does not therefore 30 appear in the conversation heard by the distant subscriber in association with whose channel the disturbance may be created.

Reception of voice currents

35 Considering now the way in which the high-frequency interspersed message groups are sorted out and reassembled into separate continuous messages at the distant exchange, it will be recalled that the distant receiving recording magnet 39 is being rotated in synchronism with the 40 reproducing transmitting magnet 28 and in phase with it except for the small time-interval displacement representing the transmission time of the voice currents over the line TL from exchange 45 1 to exchange 2. Consider now the sub-interval of time which begins when the transmitting reproducing magnet 28 of the distributor D1 is leaving the influence of erasing magnet 86 in the channel-B group. When the surge of current 50 transmitted as a result of magnet 28 passing over this erasing magnet reaches the distant exchange, magnet 39 is passing over the erasing magnet 81 in the channel-C group of magnets. When magnet 28 proceeds a little further and has left the 55 influence of the above-mentioned erasing magnet, magnet 39 is passing over the pole pieces of the stationary reproducing magnet 53 of receiving channel C in the distant exchange. Then, as magnet 28 progresses further toward the channel 60 C magnet 43 it transmits the record of the voice currents that have been received over the channel C circuit in exchange 1 during the time interval which has elapsed since magnet 28 previously contacted the channel C portion of the record. At 65 the same time, receiving recording magnet 39 of the distributor D2 is proceeding toward the channel D magnet group, including magnet 54. Just as magnet 28 arrives over the pole pieces of the channel D stationary magnet 43, magnet 39 of the distributor D2 comes under the influence of 70 the restoring magnet in the group containing magnet 54. Then, while the portion of the track disc on which a record has been impressed by the receiving recording magnet 29 during its travel in the C quadrant is reproduced and sent 75

over the C channel to the subscriber in exchange 2, magnet 39 travels over the other three quadrants. It comes again into effective relationship to quadrant C just as the last of the previously recorded portion of the message is reproduced. 5 In this way, a continuous reproduction and transmission to channel C branch in exchange 2 is accomplished. A similar result is accomplished in the same way for each of the other three channels. 10

Two-way operation

While the transmission over the four channels from exchange 1 to exchange 2 has been taking place as above described, the transmitting portion of distributor D2 has been cooperating with the receiving portion of the distributor D1 to effect a similar four-channel transmission in the reverse direction in the event that any voice currents are generated on the respective channels in exchange 2. It will be understood of course that, if the subscribers in exchange 1 cease talking and the subscribers in exchange 2 all start talking, the four-channel operation proceeds in the reverse direction in the manner described. However, it makes no difference to the operation of the distributor system whether or not voice currents are travelling in the same direction over all the channels or even whether or not they are travelling in only one direction over one channel at a time or not. Voice currents may be transmitted simultaneously in both directions over each of the channels A to D if all of the subscribers should be talking at once, which discussion is largely of academic interest except as it concerns the operation which takes place when a listening subscriber desires to interrupt the conversation of the other, possibly to interject a question. In short, the subscribers interconnected by way of the disclosed transmission system may converse as they would over any ordinary telephone connection with the one exception, that there is a variable delay of a small fraction of a second under certain conditions occasioned by the amount of time required for a recorded portion of a message to be sent through the transmitter and recorded and repeated at the receiving distributor. 30 35 40 45

Stopping and restarting

In the event that the system is to be stopped, which may logically occur during a period of light traffic, the power supply of the driving motors may be disconnected. When the system is to be restarted the two distributors may be brought into phase by rotating the frame structure of either of the driving motors. For example, by turning the worm 23 slowly the frame of the motor 4 is rotated in the proper direction to bring the central shaft 2 and the hollow shaft 3 into the same phase relationship with respect to the corresponding shafts on distributor D2 as existed during the previous operation. When the two distributors have been brought into the same phase relation that previously existed, the receiving and transmitting portions of all the channels in both directions will be in phase, and individual adjustments at the two distributors may be done away with. This operation will be understood when it is recalled that a synchronous motor maintains the speed of its rotating shaft constant with respect to the frame structure of the motor. Therefore, if the frame structure of the motor is turned so slowly as not to impose an overload on the motor, the speed of the motor shaft is increased or decreased as the case may be just enough to keep the 50 55 60 65 70 75

shaft running at a constant speed with respect to the frame of the motor, as the motor frame is turned in one direction or the other in order to bring the rotating parts of the distributor into the previously existing phase relationship.

The separate adjustments of the distributor may be made use of also in order to bring the distributors into the proper phase relationship with the magnet groups of the receiving ring of each distributor sufficiently displaced with respect to the magnet of the associated transmitting ring so as to minimize any tendency for direct inter-group aerial magnetic interference.

15 *Modified arrangements*

The system herein disclosed may obviously be refined in certain respects. For example, the amplifiers 57 and 67 may be made to include a band pass filter which will eliminate from the reproduced conversation all frequencies which exceed a set maximum, whereby the maximum frequency transmitted over the line TL from the distributor D1 is limited. This arrangement may be employed to prevent excessive cross-talk interaction between adjacent lines similarly equipped, in which case the amplifier 67 is similarly provided with an input band pass filter to limit the frequency of the currents impressed on the line TL at exchange 2.

30 A modification which at once suggests itself may include the use of a four-wire circuit between the two distributors to replace the line TL, transmission in one direction proceeding over one pair of wires and transmission in the other direction proceeding over the other pair of wires. This arrangement may be used to advantage if the line TL is sufficiently long that a great number of repeaters are required, in which case separate balancing networks at the various repeaters 40 are done away with and simple one-way amplifiers may be used, as is well known.

It will be understood that the switchboards in the two exchanges may be automatic switchboards instead of manual switchboards, in which 45 case dial impulses may be transmitted over the channels by any known method of voice-frequency dialling, such as the system disclosed in the application of John Wicks, Serial Number 751,802, filed November 7, 1934.

50 What is claimed is:

1. In a multiplex telephone transmission system, a two conductor trunk line extending between two stations, a distributor at each end of said trunk line, each distributor including a rotating disc having a transmitting and a receiving track thereon, means for magnetically recording more than one conversation on the transmitting track of each disc, means for transmitting all the recorded conversations over said 60 trunk line at a higher speed than that at which

they were recorded, means for recording a plurality of received conversations at the same time on the receiving track of each disc as received over said trunk line, and means for reproducing the conversations recorded on the receiving track, whereby a plurality of two-way conversations may be carried on over said trunk line without interference.

2. In a multiplex telephone transmission system, a two-conductor trunk line, a distributor at each end thereof, a plurality of telephone stations connected with each distributor, each distributor including a rotating disc having a transmitting and a receiving track thereon, each station having a magnet for recording outgoing voice currents on the transmitting track of its distributor, and a magnet for reproducing recorded voice currents from the receiving track, another element rotating at a greater speed than said disc, said element carrying a transmitting 20 device which transmits outgoing voice currents recorded on the disc by the magnets of all stations, and a receiving device which records incoming voice currents on the receiving track of the disc for reproduction by all the reproducing 25 magnets.

3. In a multiplex telephone system, a plurality of telephone lines, a trunk line, a distributor for recording and retransmitting incoming and outgoing conversation from the lines over the trunk line and from the trunk line to all the lines simultaneously, said distributor comprising a rotating disc adapted to receive and retain magnetic impressions of voice currents received from and transmitted to the trunk line, a magnet for 30 each line for recording on the disc and a magnet for each line for reproducing from the disc, said magnets regularly spaced around the periphery of the disc, and a pair of magnets for the trunk 35 rotated relative to the disc for reproducing recorded data from the disc and transmitting it over the trunk and for recording data on the disc received over the trunk line.

4. In a multiplex telephone system, a plurality of lines and a trunk line, a distributor for distributing simultaneous voice currents from the lines over the trunk line successively, and for distributing received voice currents over the trunk line to the lines, said distributor comprising a rotating disc having one sound track around its periphery on which voice currents from all the lines are simultaneously recorded and reproduced and transmitted over the trunk line, said disc having another sound track, concentric with the first, and means for recording all voice currents received from the trunk line, on said last sound track and reproducing and distributing them to the various lines.
